ELECTRIC HAND LANTERN

Julian A. McDermott, Corona, N.Y.

Application March 25, 1958, Serial No. 50,175

Term of patent 14 years

(Cl. D48—24)

Figure 1 is a side elevational view of an electric hand lantern, showing my new design.

Figure 2 is a front elevational view thereof.

I claim:

The ornamental design for an electric hand lantern, substantially as shown.
